UNITED STATES PATENT OFFICE.

LOYAL L. WYNN, OF FLORENCE, COLORADO.

MECHANICAL TOY.

Application filed October 3, 1924. Serial No. 741,365.

The present disclosure of the invention relates to a mechanical toy simulating a duck, but it may be stated that a number of novel features herein disclosed may be embodied also in connection with toys simulating other living creatures.

One object of the invention is to provide a toy having very lifelike movements, provisions being made in the form of construction shown to alternately turn the head from side to side, to move the lower jaw or bill section upwardly and downwardly, and to sway the body from side to side, thus effectively imitating the actions of a duck or like fowl.

Further objects are to provide novel means for turning the head, operating the lower jaw or bill section and swaying the body.

A still further object is to provide a construction in which the lower jaw or bill section is snapped upwardly against the upper jaw or bill section, each time it is lowered or released, the noise thus caused imitating the "quacking" of a duck. In this connection, a further aim is to provide the head and the upper jaw or bill section with a recess which produces a different sound from that which would be produced by permitting the lower bill section or jaw to snap upwardly against an extended flat surface, the sound produced being a rather effective imitation of a duck's "quack".

Another object is to provide a novel body construction in which two wing simulating sections, secured against opposite sides of a main body section, serve also to cover the opposite sides of a recess formed in said main section to contain certain parts of the operating mechanism.

A still further aim is the provision of a toy which will be rather simple and inexpensive, yet will be durable and will afford a great deal of amusement.

With the foregoing and minor objects in view, the invention resides in the novel subject matter hereinafter described and claimed, the description being supplemented by the accompanying drawings.

Figure 1 is a side elevation.

Figure 2 is a bottom plan view.

Figure 3 is a top plan view.

Figure 4 is substantially a central vertical longitudinal sectional view.

Figure 5 is a vertical transverse section on line 5—5 of Fig. 4.

Figure 6 is a horizontal section on line 6—6 of Fig. 4.

Figure 7 is a detail vertical sectional view cut centrally through a portion of the device, as indicated by line 7—7 of Fig. 6.

The form of construction selected for illustration in the present application is rather specifically described hereinafter with the understanding however that within the scope of the invention as claimed, numerous modifications may be made, including the possible adaptation of certain features of the toy to toys representing living creatures other than the duck illustrated in the present showing.

The numeral 1 designates a central, vertical, comparatively thick body section which simulates the body of a duck, said body having a recess 2 formed in its lower edge and opening through its opposite sides for a purpose to appear. The body 1 is also formed with a vertical bore 3 at its front end communicating with the recess 2, and in the rear portion of the body, a recess 4 is formed in which a suitable wheel 5 is mounted. If desired, this wheel may be provided with a rubber tire 6.

Two spaced disks 7 and 8 are shown within the recess 2, said disks being connected by a radially extending cam 9 and one of said disks being provided on its outer side with an eccentric 10. Axle stubs 11 extend outwardly from the disks 7 and 8 and may if desired be cast integrally therewith, or the disks and cam may be cast around a single axle-forming rod or the like, or other adequate construction may be employed. The stubs 11, in the construction shown, are upwardly inserted through slots 12 in a pair of wing simulating body sections 13 which are secured in any suitable manner against opposite sides of the body section 1, said sections 13 extending across the recess 2, to close opposite sides of the latter. By means of any suitable retainers, such as the plates 14, the axle stubs 11 are rotatably held in the slots or notches 12. The outer ends of these stubs are provided with wheels 15 which are preferably rather heavy and are provided with rubber tires 16 to obtain traction. It may here be explained that the points at which the wheels 15 are connected with the axle stubs 11, are preferably eccentric to the treads of said wheels, so that when the toy is being pulled or pushed along

a supporting surface, the eccentric wheels will cause the body to sway, thereby representing the movements of a duck when walking.

5 Received for oscillation in the bore 3, is a vertical shaft 17 which may well be formed from a piece of doweling, the shaft being retained in the bore by any suitable means, such as the transverse pin 18 passing through 10 the body and received in a slot 19 formed transversely through the shaft. The upper end of the shaft 17 is suitably secured to a head 20 which is provided with a stationary upper bill section or jaw 21 and a movable 15 lower bill section or jaw 22 which is pivoted at its rear end as indicated at 23. In the present showing, the lower side of the bill or jaw section 21 and the head 20 are formed with a recess 24 which contains a coiled tension spring 25 having its rear end anchored to the head, while its front end is connected with the lower jaw or bill section 22, for the purpose of upwardly snapping the latter against the jaw or bill section 21, each 20 time said lower jaw or bill section is pulled downwardly and released. Novel provision is made for alternately pulling the section 22 downwardly and releasing it, as herein-after described. In the simple construction 25 illustrated, a longitudinal slot 26 is formed in the bill section 22 and this slot receives the relatively narrow intermediate portion 27 of a sheet metal plate, said plate having widened ends 28 and 29 which contact respectively 30 with the upper and lower sides of said section 22. The plate is inserted through the slot 26 and is then turned so that it stands transversely of said slot, causing its widened ends 28 and 29 to hold it against any vertical 35 movement with respect to the bill section 22. The spring 25 is connected suitably with the upper end of the plate, and a wire jaw-operating link 30 is pivoted to the lower end thereof, said link being receivable in a longitudinal passage 31 which is formed in the shaft 17, said passage being preferably in the form of a groove in the front side of said shaft. The lower end of the link 30 is pivoted at 32 to a substantially horizontal 40 lever 33 which passes through an opening 34 in the lower end portion of the shaft 17. The rear end of the lever 33 is disposed in the path of the cam 9 while its front end engages the lower side of a main transverse fulcrum 35, this fulcrum being preferably 45 in the form of a pin passing across a groove 36 formed in the front wall of the recess 2. The front end of the lever 33, is preferably provided with an upstanding extension 37 50 received slidably in the groove 36 and serving to prevent dislocation of the lever with respect to the fulcrum pin 35, when the front end of said lever is moved downwardly under certain circumstances, hereinafter set forth. At a point behind the

connection 32, the lever 30 bears against the upper end 38 of the opening 34, as shown most clearly in Fig. 7, said upper end of the opening constituting an auxiliary fulcrum for the lever.

When the toy is being moved forwardly, the opposite ends of the cam 9 alternately strike the lever 33 and depress the latter to rock the lever about the fulcrum 35 thereby pulling downwardly upon the link 30 and 70 jaw 22 until the lever is released by the cam, whereupon the spring 25 immediately snaps the jaw 22 upwardly against the jaw 21, producing a noise to imitate the quacking of a duck. If the toy is moved rearwardly, the 80 cam 9 rocks the lever 33 about the auxiliary fulcrum 38 thus also pulling downwardly upon the link 30 to swing the jaw 22 downwardly and then release it. It is during this movement of the lever about the auxiliary 85 fulcrum 38 that the extension 37 of the lever 33 slides downwardly with regard to the fulcrum pin 35, preventing the lever and pin from being relatively dislocated.

While the bill section or jaw 22 is being 90 operated as above described and the body 1 is being swayed by the eccentric wheels 15, the shaft 17 is oscillated to turn the head 20 from side to side. To effect this oscillation, a pitman 39 is engaged with the eccentric 95 10 and is connected with a lateral crank 40 on the shaft 17, the latter connection being loose to permit turning of the shaft about its vertical axis.

By providing the novel construction 100 shown and described, or a substantial equivalent thereof, a toy is produced which may be easily and inexpensively manufactured and sold at small cost, yet will produce a great deal of amusement. Particular attention is directed to the fact that by having the bill section 22 provided with the raising spring 25, and alternately depressing and releasing said bill section, it is caused to quickly snap upwardly against the upper 105 section 21, effectively imitating the quacking of a duck. The sound is rendered much more natural by having the recess 24 in the head and opening through the lower side of the bill section 21. Attention is also invited to the fact that the turning of the head 20 from side to side effectively simulates the movements of a duck's head, and swaying of the body 1 by means of the eccentric wheels, is a very amusing representation of 110 115 the waddling of a duck.

As excellent results may be obtained from the details disclosed, they may well be followed, but within the scope of the invention as claimed, numerous modifications may be 120 125 made, as above suggested.

I claim:

1. A toy comprising a wheeled body simulating the body of a living creature, said body having a head provided with a station- 130

ary upper jaw and a pivoted lower jaw, spring means for upwardly snapping said lower jaw against the upper jaw, and means driven by a wheel of the body for alternately moving said lower jaw downwardly against the action of said spring means and quickly releasing said movable jaw for snapping engagement with the upper jaw to effect simulation of the sound created by the creature represented.

2. A toy comprising a body simulating the body of a living creature, said body having a head provided with a stationary upper jaw and a pivoted lower jaw, spring means for upwardly snapping the lower jaw against the upper jaw to effect simulation of the sound created by the creature represented; a wheeled axle for the body provided with a cam, a member operatively associated with said cam and adapted to be alternately moved and quickly released thereby, and a connection between said member and said lower jaw for downwardly swinging the latter against the action of said spring means.

3. A toy comprising a body simulating the body of a living creature, said body having a head provided with a stationary upper jaw and a pivoted lower jaw, spring means for upwardly snapping the lower jaw against the upper jaw, a wheeled axle for the body provided with a cam, a substantially horizontal lever having one end disposed to be alternately struck and released by said cam, a main fulcrum for the other end of the lever carried by the body and normally contacting with one side of said lever, an auxiliary fulcrum for said lever spaced inwardly from the main fulcrum, and a connection between said lower jaw and said lever connected to the latter at a point between the two fulcrums.

4. A structure as specified in claim 3; said main fulcrum consisting of a pin, said lever having a curved lateral extension transverse to and slidably engaging said pin to move thereon when the lever rocks about the auxiliary fulcrum.

5. A toy comprising a body having a head provided with a stationary upper jaw and a pivoted lower jaw, the latter having a slot, a metal plate having a narrow intermediate portion passing through said slot and having widened ends transverse to said slot and abutting the upper and lower sides of the movable jaw, a coiled spring in the head connected to the upper end of said plate for closing the movable jaw, and means connected to the lower end of said plate for lowering said movable jaw against the action of the spring and then releasing it.

6. A toy duck comprising a body having a head provided with a fixed upper bill section and a pivoted lower bill section, and spring means for snapping said lower bill section upwardly against the upper bill section each time it is lowered and released, said head and upper bill section having a recess opening through the lower side of the latter to produce an imitation of a duck's "quacking" when the lower bill section strikes the upper section.

7. A toy comprising a body having a recess and a vertical bore rising therefrom, a vertical shaft received in said bore for oscillation, a head on the upper end of said shaft, a wheeled axle for the body passing across said recess and having an eccentric, a pitman engaged with said eccentric, and a crank on the shaft connected to said pitman.

In testimony whereof I have hereunto affixed my signature.

LOYAL L. WYNN.
